(57) **CLAIM**

The ornamental design for an antenna, as shown and described.

DESCRIPTION

FIG. 1 is a top plan view of an antenna on a base in broken lines;

FIG. 2 is a side elevation view thereof;

FIG. 3 is a front elevation view thereof;

FIG. 4 is a bottom plan view thereof;

FIG. 5 is a top perspective view thereof;

FIG. 6 is a top plan view of an antenna without environment; and,

FIG. 7 is a rear elevation view thereof.

The broken lines illustrate the environment of the antenna and form no part of the claimed design.
